US00D931253S

(12) **United States Design Patent** (10) Patent No.: **US D931,253 S**
(45) Date of Patent: **** Sep. 21, 2021**

(54) **MEDIA PLAYBACK DEVICE**

(71) Applicant: **Sonos, Inc.**, Santa Barbara, CA (US)

(72) Inventors: **Dayn Wilberding**, Santa Barbara, CA (US); **Nikolai Kutateladze**, Santa Barbara, CA (US); **Stefan Reichert**, Santa Barbara, CA (US); **Dana Krieger**, Santa Barbara, CA (US)

(73) Assignee: **Sonos, Inc.**, Santa Barbara, CA (US)

(**) Term: **15 Years**

(21) Appl. No.: **29/724,472**

(22) Filed: **Feb. 14, 2020**

(57) **CLAIM**

The ornamental design for a media playback device, as shown and described.

DESCRIPTION

FIG. 1 is a front elevation view of a media playback device of the present invention.

FIG. 2 is rear elevation view of FIG. 1.

FIG. 3 is a first side view of FIG. 1.

FIG. 4 is a second side view of FIG. 1.

FIG. 5 is a top plan view of FIG. 1.

FIG. 6 is a bottom plan view of FIG. 1; and,

FIG. 7 is a perspective view of FIG. 1.

The broken lines illustrate the portions of the design that form no part of the claimed design.

1 Claim, 7 Drawing Sheets
